[57] CLAIM

The ornamental design for a piston for a pressurized dispensing container, substantially as shown and described.

DESCRIPTION

FIG. 1 is a front elevational view of a piston for a pressurized dispensing container showing my new design, the rear elevational view, right side elevational view and left side elevational view being identical in appearance to the front elevational view;

FIG. 2 is a top plan view thereof;

FIG. 3 is a bottom plan view thereof;

FIG. 4 is an exploded, front elevational view thereof;

FIG. 5 is a view thereof in longitudinal cross section of FIG. 1 as taken in a plane including a center line; and

FIG. 6 is a view similar to FIG. 2 with a dispensing container being shown in broken lines to illustrate environmental use only.

FIG. 1

FIG. 4

FIG. 2

FIG. 3

FIG. 6

FIG. 5
